UNITED STATES PATENT OFFICE.

GEORGE T. ASHWORTH, OF PHILADELPHIA, PENNSYLVANIA.

REFRIGERATOR.

1,410,543.

Specification of Letters Patent. Patented Mar. 28, 1922.

Application filed November 19, 1920. Serial No. 425,069.

To all whom it may concern:

Be it known that I, GEORGE T. ASHWORTH, a citizen of the United States, residing in the city and county of Philadelphia, State of Pennsylvania, have invented a new and useful Refrigerator, of which the following is a specification.

My invention consists of a novel construction of a refrigerator wherein I provide means for supporting the ice or cooling medium directly upon a coil having a connection with the city main or other constant water supply, provision being made by a novel construction and collocation of shelves, which terminate at a suitable distance from the front and sides of the refrigerator for enabling a plurality of compartments to be formed, which are in free communication not only with each other but also with the ice chamber, so that the cooling effect of the ice is felt in a substantially equal degree throughout the entire interior of the refrigerator and the plurality of chambers formed therein, so that the cooling effect of the ice is utilized to a maximum extent.

To the above ends, my invention consists of a novel construction of refrigerator having a plurality of superposed compartments, which are in free communication with each other and with the ice chamber, so that provision is made for the cool air to be present or to circulate in every portion of the refrigerator.

It further consists of a novel construction of a drip for the interior of the refrigerator provided at its bottom with a water seal, whereby the ingress of warm air to the refrigerator is prevented.

It further consists of other novel features of construction, all as will be hereinafter fully set forth.

For the purpose of illustrating my invention, I have shown in the accompanying drawings, certain forms thereof which are at present preferred by me, since the same will give in practice satisfactory and reliable results, although it is to be understood that the various instrumentalities in which my invention consists may be variously arranged and organized and that my invention is not limited to the precise arrangement and organization of these instrumentalities as herein shown and described.

Figure 1 represents a front elevation of a refrigerator embodying my invention, the door thereof being shown open.

Figure 2 represents a side elevation of Figure 1.

Figure 3 represents a section on line 3—3 of Figure 1.

Figure 4 represents a section on line 4—4 of Figure 2.

Figure 5 represents a section on line 5—5 of Figure 4.

Figure 6 represents on an enlarged scale 65 a sectional view of the lower portion of the refrigerator corresponding to the lower left-hand portion of Figure 4.

Similar numerals of reference indicate corresponding parts.

Referring to the drawings:

1 designates my novel construction of refrigerator, the same comprising an outer casing 2 of wood or other material, an inner lining of enamel, zinc or the like 3, and an intermediate filler of non-conducting material 4, such as charcoal or the like. The refrigerator front 5 is provided with a door opening 6 located at one side of said front, which is closed by the door 7. The top 8 is provided with a lid or closure 9 which is in vertical alignment with the ice supporting shelf 10, which latter also supports the coils 11, which have the inlet branch 12 leading thereto from a running water supply, such as a city main, the outlet from said coils 11 being indicated at 13, and leading to the spigot 14, whereby upon opening said spigot, a fresh supply of cooled running water is always available, by reason of the ice 15 being supported directly upon said coils 11.

The drip from the melted ice is conveyed through the pipe 16 to a point below the refrigerator bottom 17 and said drip pipe 95 has attached thereto the elbow or U-shaped fitting 18, which ensures a water seal at all times, so that no warm air can enter the refrigerator upwardly through said pipe 16. A pan 25 is located below the water seal 18 for catching any overflow therefrom.

The upper shelf 19, which is preferably of glass, is supported by the angles 20 or their equivalents and the rod 21. The lower shelf 22 is supported by the angles 23 and the edge 24 of the ice supporting shelf 10.

It will be seen in my invention that the front edges 26 and 27 of the shelves 19 and 22 terminate a short distance from the front 5 of the refrigerator, see figures 3 and 5, 110 so as to form a continuous opening or passageway from the bottom chamber 28 to the

intermediate chamber 29 and the upper chamber 30, and the side edges 31 and 32 of said shelves 19 and 22 terminate in proximity to the ice chamber, as seen in figure 4, so that the effect of the ice or cooling medium 15 is present throughout the entire interior of the refrigerator and is substantially equally present in the three chambers 30, 29 and 28, and there is consequently by my construction afforded a free circulation of the cool air throughout the three chambers 28, 29 and 30, in which the edibles or other articles to be cooled are placed.

15 The closure 9 not only permits the insertion of the ice, but also gives access to the upper shelf 19, and the upper chamber 30, while the opening of the door 7 permits access to the chambers 29 and 28.

20 I preferably make the shelves 19 and 22 of glass or similar material and the same can be readily removed and cleaned, as is evident, according to requirements.

It will be apparent from the foregoing 25 that all the articles contained in the refrigerator are subjected to the maximum cooling effect of the cooling medium, and that my device possesses advantages over the usual type of refrigerator commonly in 30 vogue, wherein the ice is contained in a separate chamber, whose walls do not permit the cooled air to contact directly with the articles to be cooled to the same extent as my device does.

35 The door and the lid are provided with packing to make air tight joints with the parts of the casing with which they contact.

Having thus described my invention, what I claim as new and desire to secure by Let- 40 ters Patent, is:—

1. In a refrigerator, a casing having a side opening at its top for the insertion of ice and an opening and front door at one side of its front, a side ice chamber located at 45 about the middle of said casing at one side thereof and under said top opening and having a bottom shelf, upper and intermediate aligning cooling chambers located at the side of said casing opposite to said ice

chamber and in free communication therewith, shelves 19 and 22 forming the bottoms of said upper and intermediate chambers, the inner side edges 31 and 32 of said shelves terminating in proximity to said ice chamber, while their front edges 26 and 27 terminate a short distance from the refrigerator front so that said upper and intermediate chambers communicate with each other and with said ice chamber, and a lower cooling chamber below said ice chamber and shelf 22 and extending across the entire lower portion of said casing and in free communication with said upper and intermediate cooling chambers and with said ice chamber. 50

2. In a refrigerator, a casing having an opening at its top at one side thereof for the insertion of ice, and an opening and side door at one side of its front, an intermediate side ice chamber in alignment with 70 said top opening, an intermediate side cooling chamber laterally juxtaposed in substantially horizontal alignment to said ice chamber and in free communication therewith, an upper side cooling chamber, a bottom cooling chamber extending under said ice chamber and the width of said casing, shelves for said upper and intermediate chambers, the front edges 26 and 27 of said shelves terminating at short distance from 75 the front of said refrigerator, so that said upper and intermediate chambers freely communicate, and the side edges 31 and 32 of said shelves terminating at about the middle of said casing in proximity to said 80 ice chamber, so that the latter is in free communication with said lower, intermediate and upper cooling chambers, and a coil in said ice chamber upon which the ice is supported, one end of said coil being 85 adapted to be connected to a city main, and the discharge end of said coil being connected to a spigot supported in the refrigerator wall. 90
